UNITED STATES PATENT OFFICE

WILLIAM C. CARTER, OF FLINT, MICHIGAN

CARBURETOR

Application filed February 18, 1928. Serial No. 255,313.

This invention relates to carburetors.

One object of the invention is to provide a carburetor that has three suction amplifiers, and a choking device which is of such design that when it is rendered operative, the two amplifiers that are used in the first and second stages of suction amplification will be automatically cut out of service or rendered inoperative.

10 Another object of the invention is to provide a carburetor of novel construction, in which the high suction existing in the intake above the throttle valve, when the engine is not operating under a heavy load, is utilized 15 to retard or diminish the flow of fuel to the fuel supplying device or devices of the carburetor at such times. Other objects and desirable features of my invention will be hereinafter pointed out.

20 I have herein illustrated my present invention embodied in a carburetor provided with some of the features of the carburetor described in my pending application for patent Serial No. 226,684, filed October 17, 1927, 25 but modified so as to have three stages of suction amplification. I wish it to be understood, however, that certain features of my present invention are applicable to various other types and kinds of carburetors.

20 Figure 1 of the drawings is a vertical sectional view of a carburetor embodying my present invention; and

Figure 2 is a horizontal sectional view, taken on the line 2—2 of Figure 1, looking 25 in the direction indicated by the arrows.

Briefly described, the carburetor herein illustrated comprises a well for holding an accelerating charge of liquid fuel which is in readiness to be drawn into the main passageway of the carburetor. In the event the throttle valve is opened suddenly, a liquid fuel tube or by-pass leading from a supply of liquid fuel and arranged with its upper end communicating with the main passageway of the carburetor adjacent the throttle valve in such a manner that it will supply fuel to said passageway at idle speeds and slow speeds; a liquid fuel supplying device, preferably a nozzle provided with a fixed discharge orifice; a plurality of suction ampli-

fiers for producing three stages of suction amplification, according to the position of the throttle valve; a choking device arranged so that it can be actuated to cut out of service the suction amplifiers used in the first and second stages of suction amplification; and a means for retarding the flow of fuel to said nozzle during the third stage of suction amplification when the maximum suction is being exerted on the fuel nozzle. The carburetor is also preferably constructed in such a way that the relatively high suction which exists in the intake above the throttle valve when the engine is not operating under a heavy load, is utilized to diminish or retard the flow of liquid fuel to the fuel supplying device or devices of the carburetor at such times, thereby producing a carburetor that is economical in the consumption of fuel.

In the accompanying drawings which illustrate the preferred form of my invention, 70 A designates the body casting of the carburetor which is provided with a straight, vertically-disposed bore 1 that constitutes the main passageway of the carburetor, 2 designates a throttle valve which is arranged in said main passageway adjacent the upper end of same, 3 designates an air chamber which communicates with the lower end of said main passageway, 4 designates a depending cylindrical portion on the body casting that serves as a guide for an annular float 75 5 in the bowl 6 that constitutes the float chamber of the carburetor, 7 designates an accelerating well or reservoir in the depending portion 4 of the body casting, 8 designates a tubular member projecting upwardly from the bottom of said well and provided at its lower end with openings, preferably vertically-disposed slots 9 of such length that 80 the upper ends of same terminate above the normal level of the fuel in the float chamber, represented by the dot and dash line in Figure 1, and 10 designates a fuel supplying device, preferably a nozzle, that projects upwardly into the tubular member 8 at the lower end of the same. Liquid fuel is supplied to the nozzle 10 from the float chamber 85 by a duct 11 of relatively large cross-sectional area, and liquid fuel is supplied from 100

the float chamber to the well 7 by a duct or port 12 which discharges into a fuel passageway 13 that leads upwardly to the well 7, as shown in Figure 1. Three suction amplifiers 5 B, C and D are used to produce different degrees of suction amplification on the nozzle 10 according to the position of the throttle valve 2, the amplifier B that is used to produce the high stage of suction amplification 10 preferably consisting of a venturi arranged inside of the tubular member 8, with its contracted portion surrounding the discharge portion of the nozzle 10, the amplifier C that is used to produce the intermediate stage 15 of suction amplification preferably consisting of a venturi arranged in concentric relation with the amplifier B, with the contracted portion of said venturi C surrounding the discharge end of the amplifier B, and the amplifier D preferably consisting of a venturi arranged in the main passageway 1, with the contracted portion of said venturi D normally surrounding the upper end or discharge end of the amplifier C. 20

25 The low stage suction amplifier D is mounted in the passageway 1 in such a way that it can be moved towards and away from a cup-shaped member 14 arranged at the upper end of the tubular member 8, so as to 30 reduce or cut off the admission of air to the main passageway 1 of the carburetor, and thus constitute a choking device that is used to facilitate the starting of the engine when it is cold. The intermediate stage suction amplifier C is carried by the cup 14 and is combined with the same in such a manner that when the amplifier D is spaced away from the cup 14, air can flow downwardly over the upper edge of said cup and then reverse and flow 35 upwardly through the amplifier C. One convenient way of combining the amplifier C with the cup 14 is to connect said amplifier to a horizontally-disposed flange 15 on the inner side of the cup 14 that is provided with air holes 16, as shown in Figure 2. Any suitable means can be used to move the amplifier D towards and away from the cup 14, the means herein illustrated for this purpose consisting of a rotatable device 17 mounted in 40 the body casting of the carburetor and provided at its inner end with an eccentrically-disposed pin 18 that enters a hole in the side of the amplifier D. The device 17 is provided with an actuating lever 19 and also 45 with a torsion spring 20 or other suitable means that will normally exert pressure on the device 17 in a direction to hold the movable element D of the choking device in its wide open or inactive position, as shown in 50 Figure 1. In view of the fact that the intermediate stage suction amplifier C is arranged inside of the amplifier D, and is carried by the cup 14 whose top edge co-operates with the bottom edge of the amplifier to form the 55 space through which air travels to both of the

amplifiers C and D, it will be seen that when said choking device is rendered operative by moving the amplifier D downwardly into engagement with the upper edge of the cup 14, the two amplifiers C and D that are used to produce the intermediate stage and the low stage of suction amplification will be automatically cut out of service, thus leaving only the high stage suction amplifier B operative. 70

A fuel tube 21, which is of the same general design and arrangement as the fuel tube of the carburetor illustrated in my pending application for patent previously referred to, is mounted in the body casting A of the carburetor in such a way that it forms part of a fuel duct through which fuel is conveyed from a shallow chamber 7^a beneath the accelerating well to the main passageway 1 at a point above the throttle valve when said throttle valve is closed or only partly open, 75 the shallow chamber 7^a being supplied with fuel by the port 7^b which leads from the fuel passageway 13. The lower portion of this fuel duct, just referred to, is formed by a vertically-disposed groove or bore 22 in the 80 depending portion 4 of the body casting, arranged with its lower end communicating with the shallow chamber 7^a, and with its upper end communicating with a fuel passageway 23 formed in a removable plug 24 in the body casting A, said fuel passageway 23 having a lateral inlet 23^a and also an outlet, shown in broken lines in Figure 1, that leads to the lower end of the fuel tube 21. Air is admitted to the lower end of the fuel tube 21 85 by an air port 25 formed in the plug 24 in such a manner that air will flow through the fuel passageway 23 in the plug 24 and then enter the lower end of the fuel tube 21. 90

The upper end portion of the fuel tube 21 95 is so formed that when the throttle valve 2 is closed or only partly open, fuel will pass from the upper end of said tube into the main passageway 1 at a point above the throttle valve, and air will enter said tube from the 100 main passageway 1 at a point below the throttle valve, and thus cut down or reduce the suction that is exerted on the upper end of the fuel tube 21 by the high vacuum which 105 then exists in the intake of the engine. 110 When the throttle valve is moved forwardly away from its idle position, the admission of air from the passageway 1 to the upper end of the tube 21 is cut off, thereby causing the full force of the vacuum which then exists 115 in the intake of the engine to be exerted on the upper end of the fuel tube 21 or a lateral fuel discharge opening in the same. In the carburetor herein illustrated the fuel tube 21 is open at its upper end and provided with a 120 vertically-disposed slot 26 that is presented to the main passageway 1, said slot 26 being so proportioned that when the throttle valve 125 is in its closed position, the top portion of said slot will be positioned above the throttle 130

valve, and the bottom portion of said slot will be positioned below the throttle valve.

When the engine is idling with the throttle valve in its closed position, some liquid fuel mixed with air will be drawn upwardly through the tube 21 and discharged from the upper end of said tube into the main passageway 1, at a point above the throttle valve, due to the fact that the vacuum in the intake of the engine produces a suction in the tube 21 that is exerted on the passageway 23 in the plug 24 to which air and fuel are supplied by the air port 25 and the fuel duct 22, respectively. After the throttle valve has been moved into such a position that the lower end portion of the slot 26 in the upper end of the tube 21 will be positioned above the throttle valve, the high vacuum which exists in the intake of the engine when the throttle valve is partly open will become operative for drawing fuel upwardly through the tube 21, thus increasing the amount of fuel which said tube introduces into the main passageway 1. From the foregoing it will be seen that the high vacuum which exists in the intake above the throttle valve when the engine is not operating under a heavy load, is exerted directly on the fuel tube 21, and it will also be seen that the suction in the tube 21 will be varied by a change in the position of the throttle valve.

In a certain position of the throttle valve air is drawn upwardly into said main passageway 1 through the annular opening at the contracted portion of the low stage suction amplifier D at such a velocity as to create a suction inside of the suction amplifier B that will draw air downwardly into the well 7, and thence inwardly through the vertically-disposed slots 9 in the lower end of the tubular member 8, said air picking up or absorbing more or less of the fuel in the well 7 and carrying it upwardly through the concentrically-arranged suction amplifiers into the main passageway 1 of the carburetor. When the throttle valve reaches such a position as to cause sufficient air to travel through the well 7 to keep said well dry, the air which is drawn upwardly through the annular space between the lower end of said amplifier C and the upper end of the amplifier B which it surrounds, creates a suction on the nozzle 10 of sufficient intensity to cause fuel to be drawn out of said nozzle and carried upwardly into the main passageway 1. As the throttle valve continues to move towards its open position, the velocity of the air that is drawn into the lower end of the high stage suction amplifier B through the vertical slots 9 in the tubular member 8 is materially increased, thereby causing the fuel which is drawn out of the nozzle 10 to be effectively broken up and mixed with air. In a carburetor of the construction above described there is one stage of suction amplifica-

tion in which the air that is drawn upwardly through the contracted portion of the suction amplifier D produces sufficient suction to cause air to travel through the well 7 and keep said well dry; there is another stage in which the air that is drawn upwardly through the contracted portion of the amplifier C produces a suction that causes fuel to be drawn upwardly out of said nozzle 10 and discharged into the main passageway 1 of the carburetor, and there is still another stage in which air traveling at a very high velocity rushes upwardly through the annular space between the contracted portion of the amplifier B and the discharge portion of the nozzle 10, with the result that the fuel discharged from the nozzle will be broken up and thoroughly mixed with the air that is entering the main passageway 1 of the carburetor.

The fuel discharge orifice 10^a of the nozzle 10 is made large enough to prevent it from becoming easily clogged or stopped up by foreign matter in the fuel that flows through the same, and in order to prevent said orifice from supplying an excessive amount of fuel at the high stage of suction amplification, when air is traveling at a high velocity upwardly around the discharge portion of the nozzle, I provide the carburetor with a means that effectively retards or cuts down the supply of fuel to the nozzle 10 at such times.

The means that I have herein illustrated for accomplishing this result consists of an air port or passageway 27 that establishes communication between the upper portion of the float chamber of the carburetor and the upper portion of the well 7. During the high stage of suction amplification the air that is drawn downwardly through the well 7 and thence upwardly through the suction amplifier B, travels at such a high velocity that it will suck air out of the upper portion of the float chamber and produce a partial vacuum in the float chamber above the surface of the fuel therein, thereby exerting a sufficient upward pull on the fuel in the float chamber to retard the flow of the fuel to the nozzle 10. Accordingly, notwithstanding the fact that said nozzle is provided with a relatively large fuel discharge orifice 10^a, said orifice will not supply an excessive quantity of fuel during the high stage of suction amplification, because at such times the flow of the fuel from the float chamber to the nozzle 10 is choked, reduced or diminished by the minus pressure which is created in the upper portion of the float chamber by the stream of air which travels downwardly through the well 7, and then reverses and flows upwardly through the high stage suction amplifier B. The passageway 27 performs another function, in that it balances the suction on the fuel orifice 12 that leads from the float chamber and permits the fuel to flow by gravity from the float chamber to the well 7 and to the shallow

chamber 7^a. This is advantageous, in that it prevents the fuel tube 21 from supplying an excessive amount of fuel to the main passageway 1, even though an abnormally high 5 suction is created in the fuel tube 21, because, irrespective of the suction existing in said tube, said tube will only be supplied with as much fuel as is capable of feeding to the chamber 7^a by gravity.

10 Another feature of my invention which I believe to be novel is making use of the high suction that exists in the main passageway 1 of the carburetor, above the throttle valve, when the engine is not operating under a 15 heavy load, to check the flow of fuel from the float chamber to the fuel supplying device or devices of the carburetor, thereby tending to make the carburetor economical in the consumption of fuel by preventing a rich supply 20 of fuel at a time when it is not needed. In the carburetor herein shown I obtain this highly desirable result by arranging an air passageway 28 between the upper portion of the float chamber of the carburetor and the 25 fuel tube 21, the air passageway 28 being herein illustrated as leading from the underside of the top wall of the float chamber to an annular groove 28^a in the exterior of the plug 24 which registers with the lower end of the 30 fuel tube 21. It will, of course, be understood that the passageway 28 is so proportioned or designed that the suction in the tube 21 will produce a minus pressure in the float chamber above the level of the fuel in same at the 35 same time said suction is causing fuel to be drawn upwardly through the fuel passageway 22. One means that can be used to regulate the suction which the tube 21 exerts on the float chamber above the level of the fuel 40 therein, consists of an air bleeder 28^b for admitting air to the passageway 28. As previously stated, the high suction that exists in the intake above the throttle valve 2, when said valve is in its closed or partly closed position, is exerted on the fuel tube 21, and as the air passageway 28 communicates with the lower end of said fuel tube, this high suction in the intake will tend to produce a minus pressure in the float chamber above the level 45 of the fuel therein, with the result that the flow of fuel to the device which at this period in the cycle of operations of the carburetor constitutes the source of fuel supply, is checked or retarded. As soon as the vacuum 50 in the intake above the throttle valve diminishes, by a change in the position of the throttle valve, the upward pull which the suction in the tube 21 exerts on the body of fuel in the float chamber diminishes, with the result that the fuel in the float chamber is no longer subjected to the influence of the means that tends to retard the flow of the same from the float chamber when the engine is not operating under a heavy load. Bearing in mind that a 55 change in the position of the throttle valve 2

effects a change in the degree of suction of the tube 21, it will be seen that in such a carburetor the movement of the throttle valve from its open towards its closed position causes the fuel in the float chamber to be subjected to the influence of a means that tends to retard the flow of the fuel from the float chamber to the fuel supplying device or devices of the carburetor, and that the movement of the throttle valve from its closed towards its open position automatically renders this retarding means inoperative or ineffective.

In view of the fact that it is highly desirable to have the fuel flow freely from the float chamber when the engine is cold, I provide the carburetor with a controlling valve 29 for the passageway 28 which is so constructed and arranged that it will remain closed when the carburetor is cold, and will open automatically when the carburetor is warmed by the heat that radiates from the engine. Any suitable type or kind of thermostat can be used for controlling the valve 29, such, for example, as a lever 30 formed from metals having different co-efficients of expansion, and connected at one end by means of a fastening device 31 to the underside of the top wall of the float chamber, the valve 29 being mounted on the free end of said lever, as shown in Figure 1. When said lever becomes warm it will flex in a direction to open the valve 29 and hold it open, and when said lever thereafter cools off, it will flex in the opposite direction to close said valve.

Having thus described my invention, what I claim as new and desire to secure by Letters Patent is:

1. A carburetor provided with an accelerating well, a tubular member projecting upwardly through said well, substantially vertically-disposed slots in the lower end portion of said member, projecting upwardly from the bottom of the well and terminating at a point above the normal level of the fuel in the well, whereby air and fuel can pass simultaneously from the well into said tubular member, a fuel supplying device arranged inside of said tubular member, a suction amplifier associated with said fuel supplying device for increasing the velocity of the air flowing from said well into said tubular member, a fuel supplying device arranged inside of said tubular member, a suction amplifier associated with said fuel supplying device for increasing the velocity of the air flowing from said well into said tubular member at one stage of the cycle of operations of the carburetor, and a passageway for establishing communication between said well and the float chamber above the level of the fuel in said chamber.

2. A carburetor provided with a main passageway, a throttle valve for said passageway, a liquid fuel supplying device, a plurality of tubular suction amplifiers arranged in concentric relation with each other between said throttle valve and fuel supplying device, for producing different stages of velocity of the air that draws fuel out of said device, two of said amplifiers having a com-

mon air inlet, and means for moving one of said amplifiers to close said inlet to facilitate easy starting of the engine on which the carburetor is used.

5. A carburetor provided with a liquid fuel supplying device, three tubular suction amplifiers arranged in concentric relation for producing different stages of velocity of the air that is used to draw fuel out of said device, means for moving one of said suction amplifiers relatively to the one located adjacent the same, and a part combined with said adjacent amplifier that co-operates with the movable amplifier to render both of said amplifiers inoperative or ineffective to facilitate starting the engine on which the carburetor is used.

10. A carburetor provided with a main passageway, a fuel supplying device, a throttle valve in said passageway, three suction amplifiers arranged in concentric relation for producing different stages of velocity of the air that is used to draw fuel from said device, the low stage amplifier being movably mounted in the main passageway below the throttle valve, and a part combined with the intermediate amplifier that co-operates with the low stage amplifier to cut both of said amplifiers out of service so as to facilitate 15 starting the engine on which the carburetor is used.

15. A carburetor provided with a main passageway, a fuel supplying device, a plurality of tubular suction amplifiers arranged in concentric relation for producing different stages of velocity of the air that is used to draw fuel from said device, a substantially cup-shaped member on the intermediate stage amplifier that is normally spaced away 20 from the low stage amplifier so as to provide a passageway through which air is admitted to both of said amplifiers, and means for moving the low stage amplifier towards and away from said cup-shaped member, for the 25 purpose described.

45. WILLIAM C. CARTER.
